UNITED STATES PATENT OFFICE

CORNELIUS W. VAN RANST, OF AUBURN, INDIANA, ASSIGNOR, BY MESNE ASSIGNMENTS, TO MANNING & CO., OF CHICAGO, ILLINOIS, A CORPORATION OF ILLINOIS

DESIGN FOR AN ESCUTCHEON PLATE FOR AUTOMOBILE INSTRUMENT BOARDS

Application filed June 8, 1929. Serial No. 31,599. Term of patent 7 years.

To all whom it may concern:

Be it known that I, CORNELIUS W. VAN RANST, a citizen of the United States, and a resident of Auburn, county of De Kalb, and State of Indiana, have invented a new, original, and ornamental Design for an Escutcheon Plate for Automobile Instrument Boards, of which the following is a specification, reference being had to the accompanying drawing, forming a part thereof, and wherein—

Fig. 1 is a view in front elevation of an

escutcheon place for automobile instrument board showing my new design, Fig. 2 is a horizontal section through the same on the line 2—2 of Fig. 1, and Fig. 3 is a vertical section through the same on the line 3—3 of Fig. 1.

I claim:—

The ornamental design for an escutcheon plate for automobile instrument boards substantially as shown.

CORNELIUS W. VAN RANST.
